APPARATUS FOR FORMING CARTONS

Harry E. Hines, Monroe, Mich., assignor to Consolidated Paper Company, Monroe, Mich., a corporation of Michigan

Application January 29, 1940, Serial No. 316,192

24 Claims. (Cl. 93—55.1)

This invention relates to setting up receptacles.

This invention has utility when incorporated in opening out flat or knock-down carton sections, setting a partition or end in the side walls or tubular portion terminal region thereof, and anchoring the partition or end in such set-up package section, thereby to form an open top receptacle ready for charging contents therewith.

Referring to the drawings:

Fig. 1 is a view of the scored blank from the inner side thereof;

Fig. 2 is a showing of the scored blank of Fig. 1 as assembled into a flattened-out endless section;

Fig. 3 is a plan view of the base or platform against which the opened-out tube has its short flaps jammed to effect folding of such inward;

Fig. 4 is a fragmentary vertical section through the container as jammed against the base or platform;

Fig. 5 is a detail view of the end closure or partition to be seated in the tubular portion against the inwardly extending flaps of Fig. 4;

Fig. 6 is a view similar to Fig. 4 with the partition angularly in the tubular portion with the tool projected theretoward;

Fig. 7 is a view similar to Fig. 6 in which the tool has effected the thrusting of the partition into the seat or angle against the endless series of end flaps;

Fig. 8 is a section on the line VIII—VIII, Fig. 7, showing the spread-tool over the partition in the cylindrical tube container;

Fig. 9 is a side elevation of the stitching device to receive the partially set up container;

Fig. 10 is a section on the line X—X, Fig. 9, at the table top;

Fig. 11 is a section on the line XI—XI, Fig. 9, showing features of the intermittent drive; and

Fig. 12 is a view of a completed carton end.

In the carrying out of the invention herein, sheet fiber board, box board, or paper board stock may provide major side 1, secondary side 2, and still minor side 3 (Fig. 1), which is assembled by stitching 4 to provide side walls 5 (Figs. 2, 4) for a container. Scoring 6, 7, determine a fold region for the knock-down tubular blank to be in flat condition for stacking and shipping. Scoring 8 is at the base of major flaps 9 as endless annular series for the end closure portion of the container, which closure is to be effective after the container is charged or filled. Score 10, remote from the score 8, is slightly spaced from endless annular series of

minor flaps 11. The anchoring means or stitching or stapling 4 brings the terminus of the minor inner side 3 to overlap the terminus of the larger side 2. This preserves the symmetry for the flaps 11 and locates at the region of the stitching 4, but therebeyond, fractional flap 11' (Fig. 1) which has its tapered side 11'' extend from the tip of the flap 11' to the scoring 10. This means that this incline at the terminus of the section 3 is of greater extent than the sides of V-cuts 15 which separate the flaps 11 but which V-cuts do not extend clear to the scoring 10. Accordingly, there is at the assembly or stapling 4 a double thickness for at least a fraction of the tab or flap, but the symmetry of the tabs or flaps is continuous. In the carrying out of the invention herein, this knock-down or flat tubular structure (Fig. 2) may be spread or opened out and the side walls 5 (Fig. 4) then thrust toward base 12 having shallow inwardly tapered portion 13. The scoring 10, with the clearance 14 as to the V-cuts 15 between the flaps 11, controls the flaps 11 against outward thrusting so that in this jamming there is an inward drawing to have these flaps radiate inward on the base 12. The sides of the V-cuts 15 and the slant of the side 11'' are at an acute angle to the direction of the scoring 10, while the V-cuts 15 do not extend clear to the scoring 10 but are short therefrom. Partition 16 may then be dropped into this region between the side walls 5.

For facility in locating this partition, tool is provided having grip or handle 17 and stem 18 (Fig. 6) with loose guide 19 thereon having diametrical arms 20 to pivot connections 21 with semi-circular sections 22 having intermediate hinge 23. This tool as thrust down centrally between the side walls 5 against the partition 16 so flattens out this partition 16 that its rim portion registers with the scoring 10 adjacent the flaps 11.

Helpful in carrying out this invention is machine having upright frame portion 24 (Fig. 9) from base 25. This upright portion 24 has overhanging arm 26, terminally of which is located stitcher 27, above which is located supply reel 28 for wire 29, say of flat stock adapted to be cut into lengths and terminally bent over as a two-pointed tack in staple-like type of stitch. Motor 30 has transmission 31 to drive the stitcher and additionally drive cam 32. This cam 32 thereby synchronizes with the stitcher 27 in operation of lever 33 having adjustable fulcrum 34 in arm 35 from the upright frame portion 24.

Tension helical spring 36 having adjustment 37 as to the frame 24 engages the lever 33 to hold such in position as to the cam 32. This lever 33 has at its lower arm 38 slot 39 connected to link 40. This link 40 has connection to arm 41 (Fig. 11) pivoted on shaft 42. Carried by this arm 41 is pin 43 pivotally mounting pawl 44, normally thrown by spring 45 into mesh with ratchet 46 fixed on the shaft 42 (Fig. 9).

On the base 25 is bearing 47 mounting column 48 having thereon lower deck or holder 49 and upper deck or holder table 50. This cam 32 through this lever and linkage mechanism is an intermittent grip device to provide step by step rotation of the shaft 42 having bearing in the table portions 49, 50. Table portion 50 has spaced therefrom parallel portion 51. In the clearance region 52 between the portions 50, 51, is located friction roller 53 fast on the shaft 42.

The location of the table portion 49 is at such spacing from the table portion 50 that as the tubular section 5 has its end closing partition 16 rest on the table 50 with the tube portion 5 downward therefrom, the flaps 9 as straight therefrom abut this table 49. From the overhanging arm 26 there is depending bracket 54 (Fig. 10) which has pivot bearing 55 mounting lever 56 having roller 57, normally held against the position of the roller 53, because arm 58 fixed with the arm 56 of this angle lever is connected to tension spring 59 to an extension 60 from the bracket 54. Handle 61 may serve to shift this roller 57 for increased spacing as to the roller 53 and thereby clear of the stock or work as on the holder.

In placing this stock or work on the holder, the upper tables 50, 51, are pulled away from the stitcher 27 and thereby rocked on the pivot 47. In this cleared position for placing the work on the tables, the tables may then be rocked back so that abutment 62 strikes adjustable stop 63 at the desired upright position to bring anvil 64 in the table 50 at appropriate register position as to the stitcher working tool 65. The table and work are normally held in this registry position as to the anvil and stitcher as rocked to have the abutment 62 against the stop 63. This normal holding is effected by tension spring 66 between the upright frame 24 and the column 48. The operator, by depressing treadle 67, operates control mechanism so that the motor 30 is effective through the transmission 31 to drive the stitcher 27 for its tool 65 to impale toward the anvil 64 in thrusting a staple through the work to be clinched by the anvil 64. As such operation is completed and the tool 65 is withdrawn, the cam 32 is effective in this intermission to operate the intermittent grip device to shift the work for a step of progress or rotation due to the friction action of the roller 53 upon the stock as held thereagainst by the roller 61. The tables do not rotate but have their only position of change that of rocking. The work is given this step by step for the desired advance, whether the stapling be to bridge between the flaps 11, or medially of the flaps, or in both places.

As the operator notes the stitching has been completed for the circuit, the treadle 67 is released and the machine stopped so that the work may be pulled away from position beneath the stitcher. The stitch-anchored partition at the end of the carton is thus, as a unit, slipped off the inclined set of tables 49, 50, as tilted away from the stitcher 27. All is now in readiness for slipping a succeeding set-up of carton with the par-

tion located therein. As such partition 16 is against the table portion 50 and the free ends of the flaps 9 abut the table portion 49, the spring 65 may be effective to swing these tables back to have the column 48 upright and the anvil 64 located in position as to the stitcher 27. The operator may then depress the treadle 67 for a repetition of the cycle of operation.

In practice, it is convenient that there be a range of operation herein, as well as a range for taking care of different dimension containers. Such range as to length is effected by locating different spacing between the upper table portion 50 and the holder table portion 49. The matter of transverse dimension which could mean variation in the diameter is readily taken into account by the friction wheel 53 as cooperating with roller 57 holding the container in position against relatively controlled shifting as to the table 50 in the vicinity of the anvil 64. In practice, there may be purpose in locating staples 68 in the joints between the flaps 11 to bridge therebetween (Fig. 12) or even centrally of the flaps. This location is taken into account by varying the throw of the intermittent grip device through adjustment 69 in the link 40.

With the carton in position as to its tubular portion about the table 50 and the end or partition 16 against the table 50, the flaps, whether previously jammed or directed by guide 70 (Fig. 9), are in proximity to this end 16 as the respective flaps are fed into position as to the stitcher 27.

What is claimed and it is desired to secure by United States Letters Patent is:

1. A machine frame, an overhanging arm therefrom, a stitcher terminally of the arm, a work holder table carried by and movable relatively to the frame and including an anvil to oppose the stitcher, a drive on the frame for the stitcher, a transmission connection from the drive synchronized to advance the work on the table at release positions of the stitcher as to work on the table.

2. A machine frame, an overhanging arm from the frame, a stitcher terminally of the arm, a tiltable table carried by the frame and opposing the stitcher, whereby the table may be shifted clear of the stitcher to receive an article of work, and then be swung back to bring the work into cooperative position with the stitcher, a drive on the frame for the stitcher, an intermittent grip transmission connection from the drive synchronized with the stitcher to shift work on the table as to the stitcher at release position of the stitcher as to said work.

3. For a tubular carton having an endless series of flaps provided with scoring on the inner side adjacent the flaps and a partition seated at the scoring; a holder providing an anvil to abut the partition adjacent the flaps, stitching means opposing the anvil for anchoring the flaps to the seated partition, a drive for the stitching means having connection for effecting relative progress between the holder and stitcher, and release means for clearing the holder from the stitcher for ready removal of the stitched carton and its replacement by a carton to be stitched.

4. For a tubular carton having an endless series of flaps provided with scoring on the inner side adjacent the flaps and a partition seated at the scoring; a holder providing an anvil to abut the partition adjacent the flaps, stitching means opposing the anvil for anchoring the flaps to the seated partition, a drive for the stitching means

having synchronized connection for shifting the holder at release position of the stitching means as to the carton, and a tilting device for the holder to clear the holder from the stitcher for ready removal of the stitched carton and its replacement by a carton to be stitched.

5. A stapling mechanism for tubular containers having flat closure elements adapted to be secured to a tubular body blank provided with tab parts extending from the body blank and arranged, when folded down, to overlap the flat closure element, said stapling mechanism comprising a staple driving mechanism, a staple clinching anvil, a table adapted to support a tubular container for rotation with respect to the stapling mechanism, means for positioning the container on the table, whereby, upon rotation of the container, successive edge portions of the container and closure element will be presented to the stapling mechanism and means operative upon movement of the container to move the tabs on the tubular body from aligned position with the tubular body wall into flatwise engagement with the closure element to present successive portions thereof to the stapling mechanism.

6. A stapling mechanism for tubular containers having flat closure elements adapted to be secured to a tubular body blank provided with tab parts extending from the body blank and arranged, when folded down, to overlap the flat closure element, said stapling mechanism comprising a table adapted to support a tubular container for rotation, a staple driving mechanism, a staple clinching anvil, drive means for positioning the container on the table, guide means directing successive edge portions of the container toward the closure element to be presented to the stapling mechanism, and means operative upon movement of the container to move the tabs on the tubular body from aligned position with the tubular body wall into flatwise engagement with the closure element to present successive portions thereof to the stapling mechanism.

7. A stapling mechanism for tubular containers having overlapping closure forming parts closing an open end of the container, said stapling mechanism comprising, in combination, a table, a base element, bearing-providing mounting means for supporting the table on and for movement relatively to the base element, a staple driving head, a staple clinching anvil comprising a post supported on the base element movable with and projecting upwardly from the table, said clinching anvil post having its upper portion away from the center of the container and adjacent the outer portions thereof.

8. A stapling mechanism for tubular containers comprising a horizontal table, a base element supporting said table, a staple driving mechanism, a clinching anvil post supported on the base portion, extending from the table and arranged to cooperate with the staple driving mechanism whereby staples may be inserted through overlapping container parts at an end of a tubular container, means for mounting the table support and the clinching anvil post to rack into and out of operative position with respect to the staple driving mechanism, whereby the table and clinching anvil post may be moved to an inoperative position, in which the clinching anvil is separated from the staple driving mechanism and driving means for rotating the container.

9. A stapling mechanism for tubular containers 75 sure disc adapted to be secured to the wall of

comprising, in combination, a base element, a horizontal table, bearing-providing tiltable mounting means for supporting the table on and for movement relatively to the base element, a staple driving mechanism, a clinching anvil post having connection for movement with the table on the base element, said post extending from the table and arranged to cooperate with the staple driving mechanism whereby staples can be driven through successive overlapping container parts at an end of a tubular container, driving means for actuating the mechanism and rotating the container, there being a portion of said driving means adapted to have an additional movement to impair transmission cooperation whereby the table and clinching anvil post may be tilted to an inoperative position in which the clinching anvil is separated from the staple driving mechanism.

10. A stapling machine for tubular containers having flat closure elements adapted to be secured to a tubular body blank provided with tab parts extending from the body blank and arranged, when folded down, to overlap the flat closure element, the stapling mechanism comprising staple driving means, a staple clinching anvil, means for supporting a container in operative relation to the staple clinching anvil, means for rotating the container supporting means to bring successive portions of a container into operative relation with the staple driving mechanism and clinching anvil, means for moving the clinching anvil and container supporting means to a position in which the container on the container supporting means will be maintained out of operative relation to the staple driving mechanism, and means for disconnecting the container rotating means to allow the clinching anvil and container supporting means to be moved to such inoperative position.

11. A stapling mechanism for tubular containers having overlapping closure forming parts closing an open end of the container, said stapling mechanism comprising, in combination, a staple driving mechanism, a staple clinching anvil, bearing-providing tiltable mounting means for supporting the anvil and a container around the clinching anvil, thereby permitting the movement of the clinching anvil and container supporting means into and out of operative relation with the staple driving mechanism, means for rotating the container to present successive parts of a container to the staple driving mechanism, and means for holding the clinching anvil in operative position.

12. A stapling mechanism for tubular containers having overlapping closure forming parts for closing an open end of a container, said stapling mechanism comprising, in combination, a staple driving mechanism, a clinching anvil, movable means for supporting a container for rotation to bring successive portions thereof into operative relation with the staple driving mechanism and clinching anvil movable with said means, means for rotating the container in step-by-step relation, means for driving staples when the container is stationary between periods of movement, and means for disconnecting the operation of the container rotating means and actuation of the staple driving mechanism.

13. A stapling mechanism comprising, in combination, staple driving means, a table for supporting a cylindrical container having a flat clo-

the container by attaching flaps overlapping the closure disc, a clinching anvil post having an anvil surface disposed in operative position with respect to the staple driving mechanism, a base element, bearing-providing movable mounting means for the table and post on the base element for shifting the table and post sufficiently clear of the staple driving means to permit a container to be placed on the table, means associated with the table for clamping a container thereon, the clamping means gripping against the inside and outside surfaces of the container walls, and an actuator for operating the clamping means to rotate the container to present to the staple driving mechanism successive portions of the closure of a container.

14. A stapling mechanism for tubular containers having overlapping closure forming parts for closing an open end of the container, said stapling mechanism comprising in combination, a base, a staple driving mechanism, a staple clinching post, bearing-providing tiltable mounting means for supporting the post on the base, said post having a clinching anvil surface disposed in operative relation to the staple driving mechanism, and a container supporting member assembled for movement with the post and including means for progressively positioning a container opposite the staple clinching post.

15. A stapling mechanism for tubular containers having overlapping closure forming parts for closing an open end of a container, said stapling mechanism comprising, in combination, a base, a staple driving mechanism, a movably mounted clinching anvil, movable means for supporting a container for rotation to bring successive portions thereof into operative relation with the staple driving mechanism and clinching anvil, means for rotating the container in step-by-step relation, means for controlling the staple driving mechanism to drive staples when the container supporting means is stationary between periods of movement, said container supporting means being adjustably supported for movement with the anvil and with respect to the staple driving mechanism, and trip means for disconnecting the operation of the container rotating means and the actuation of the staple driving mechanism.

16. A stapling mechanism for cylindrical containers having flat closure element adapted to be secured to a cylindrical body blank provided with a plurality of tabs extending from the body blank and arranged, when folded down, to overlap the closure element, the stapling mechanism comprising staple driving means, a movable staple clinching anvil, a movable table adapted to be moved with the anvil and to support the cylindrical container on an open end to present the other end in proper relation to the staple driving mechanism, driving means for rotating the container in step-by-step relation, and means for synchronizing the driving of staples so that a staple is driven into a tab when the table is stationary between periods of movement.

17. A stapling mechanism for a tubular container having a flat closure element adapted to be secured to a tubular body blank provided with tab parts extending from the body blank and arranged, when folded down, to overlap the flat closure element, said stapling mechanism comprising a table adapted to support a tubular container, a staple driving mechanism, a staple clinching anvil, between which staple driving

mechanism and clinching anvil the table may locate tab parts on a closure element of the container, intermittent drive means for progressing the container relatively to the anvil, whereby successive edge portions of the container and closure element are presented to the stapling mechanism, and means operative upon movement of the container to move the tabs on the tubular body from aligned position with the tubular body wall into flatwise engagement with the closure element to present successive portions thereof to the stapling mechanism.

18. A stapling mechanism for a tubular container, said stapling mechanism comprising, in combination, a table, a base element supporting the table for movement relatively thereto, a staple driving head, a staple clinching anvil comprising a post supported on the base element and projecting upwardly from the table and having movement therewith relatively to the driving head, said clinching anvil post having its upper portion away from the center of the container and adjacent the outer portions thereof.

19. A stapling mechanism for a tubular container having tab parts extending therefrom and an end section, said mechanism comprising a horizontal table, a base element supporting said table, a staple driving mechanism, a clinching anvil post supported on the base element, extending from the table and arranged to cooperate with the staple driving mechanism whereby staples may be inserted through overlapping container parts at an end of a tubular container, there being a rockable mounting adapting the table support and the clinching anvil post to rock on the base element into and out of operative position with respect to the staple driving mechanism, whereby the table and clinching anvil post may be moved to an inoperative position, in which the clinching anvil is separated from the staple driving mechanism, and driving means for progressing the container.

20. A stapling mechanism for tubular containers having container parts overlapping an end section, said mechanism comprising, in combination, a base element, a horizontal table tiltably supported on the base element, a staple driving mechanism, a clinching anvil post, and bearing-providing tiltable mounting means for supporting the post and table on the element, whereby the table and clinching anvil post may be tilted to an inoperative position in which the clinching anvil is separated from the staple driving mechanism, said post extending from the table and arranged to cooperate with the staple driving mechanism whereby staples can be driven through successive overlapping container parts at an end of a tubular container, driving means for actuating the mechanism and rotating the container, there being a portion of said driving means adapted to have an additional movement to impair transmission cooperation.

21. A stapling mechanism for a tubular container having overlapping closure forming parts closing an open end of the container, said stapling mechanism comprising, in combination, a staple driving mechanism, a staple clinching anvil, a base element, tiltable mounting means for supporting a container around the clinching anvil, said mounting means and anvil being rockably mounted on the base element, thereby permitting moving of the clinching anvil and container supporting means into and out of operative relation with the staple driving mechanism,

means for rotating the container to present successive parts of a container to the staple driving mechanism, and means for holding the clinching anvil in operative position.

22. A stapling mechanism for a tubular container having overlapping closure forming parts for closing an open end of the container, said stapling mechanism comprising, in combination, a base, a staple driving mechanism, an opposing relatively shiftable anvil, and a container supporting member, an actuator for progressively positioning a supported container relatively to the anvil, and bearing-providing tiltable mounting means for the member and anvil on the base for effecting movement of the container with the anvil into and out of operative stapling position.

23. A stapling mechanism for a tubular container having overlapping closure forming parts for closing an open end of the container, said stapling mechanism comprising, in combination, a base, a staple driving mechanism, an opposing relatively shiftable anvil, and a container supporting member, an actuator for progressively positioning a supported container relatively to the anvil, and bearing-providing movable mount-

ing means for the member and anvil on the base and thereby adapted for shifting of the container with the anvil into and out of operative stapling position.

- 5 24. A stapling mechanism comprising, in combination, staple driving means, a table for supporting a cylindrical container having a flat closure disc adapted to be secured to the wall of the container by attaching flaps overlapping the closure disc, a clinching anvil post having an anvil surface disposed in operative position with respect to the staple driving mechanism, a base element, bearing-providing movable mounting means for the table and post on the base element 10 for shifting the table and post sufficiently clear of the staple driving means to permit a container to be placed on the table, means associated with the table for clamping a container thereon, the clamping means gripping against the inside and 15 outside surfaces of the container walls, and an actuator for operating the clamping means to rotate the container to present to the staple driving mechanism successive portions of the closure of a container.
